(57) **CLAIM**

The ornamental design for a bottle, as shown and described.

DESCRIPTION

FIG. 1 is a first perspective view of a bottle;
 FIG. 2 is a second perspective view of the bottle of FIG. 1;
 FIG. 3 is a front elevation view of the bottle of FIG. 1;
 FIG. 4 is a rear elevation view of the bottle of FIG. 1;
 FIG. 5 is a left side elevation view of the bottle of FIG. 1;
 FIG. 6 is a right side elevation view of the bottle of FIG. 1;
 FIG. 7 is a top plan view of the bottle of FIG. 1; and,
 FIG. 8 is a bottom plan view of the bottle of FIG. 1.
 The evenly broken lines (dash-dash lines) shown in the
 Figures are only for illustrative purposes to show visible
 environmental structure and form no part of the claimed
 invention.

1 Claim, 7 Drawing Sheets(56)
